[57] ABSTRACT

A brake for a wire reel comprises a brake arm including a wire guide and a brake shoe pivotably mounted to a base. The brake shoe establishes initial contact with the reel in its normal position and applies a negligible brake force thereto. Wire from the reel is fed under the wire guide. A removal force or tension applied to this wire moves the brake shoe away from contact with the reel to allow free rotation thereof. Release of the tension causes the brake shoe to return to the initial contact position whereupon subsequent rotation of the reel wedges the shoe into a braking contact position to stop the rotation. The brake applies a braking force in only one direction of rotation and will operate when the reel is mounted for rotation about either a horizontal or vertical axis.

FIG. 1

FIG. 2

BRAKE FOR A WIRE REEL

BACKGROUND OF THE INVENTION

1. Field of the Invention

This invention relates to wire handling apparatus and more particularly to a brake for controlling the removal of wire from a reel.

2. Description of the Prior Art

Telephone central offices use wire for making cross-connections on the main distributing frame and similar applications. Reels of wire are rotatably mounted to the main frame, floor, or other appropriate support means and wire is removed therefrom by pulling on the end of the wire causing the reel to rotate and unwind the wire thereon. In order to prevent wire overrun and consequent entanglement and waste of wire, braking means must be provided on the wire reel for stopping the rotation thereof when the pulling or removal force is removed from the wire.

Various types of brakes exist for controlling the payout or unwinding of wire from the reel. One of these is a drag brake or constant friction brake which applies a constant braking force to the reel which must be overcome by the wire in order to remove wire from the reel. The constant drag force applied by such brakes is difficult to adjust satisfactorily because the drag must be high enough to prevent excessive wire overrun and yet low enough to allow removal by reasonable pulling force. Another disadvantage is that such brakes tend to wear out relatively quickly because of the constant drag force applied thereby.

Another commonly used wire reel brake utilizes a brake arm having a wire guide at the end thereof through which wire from the reel is fed. The brake arm is pivoted about an axis parallel to the axis of the reel and the weight of the arm is selected to pivot a brake shoe into contact with the periphery of the reel flange when the tension or removal force is released from the wire. One disadvantage of such a brake is the uneven or jerky braking action exhibited thereby during the removal of relatively long segments of wire. Any momentary release of tension in the wire causes the brake to apply a relatively hard braking force which tends to jerk the wire from the installer's hands. Another disadvantage is that such a brake will not function when the reel is mounted for rotation about a vertical axis because the weight of the pivoted brake arm is not applied in the proper direction to pivot the brake shoe into contact with the periphery of the flange. Still another disadvantage of such a brake, as well as the drag brake previously discussed, is that the braking action is applied regardless of the direction of rotation of the reel. Thus, the rewinding of wire onto the reel requires that the braking force be overcome.

Accordingly, it is an object of this invention to improve brakes for wire reels, to provide for easy removal of the wire from the reels, and smooth application of the braking force.

Another objective is to provide a brake which can be utilized with wire reels having either horizontal or vertical axes of rotation.

Still another object is to provide a brake which applies a braking force to the reel in only one direction of rotation.

SUMMARY OF THE INVENTION

The foregoing objects and others are achieved in accordance with the invention by a brake comprising a 5 brake arm including a wire guide and a brake shoe on the end thereof. The brake arm is mounted between the flanges of the wire reel for rotation about an axis perpendicular to the axis of the reel so that the brake shoe makes an initial contact with the reel along a relatively 10 small area and hence applies a negligible braking force in this initial contact position. Wire being removed from the reel is fed beneath the wire guide. When a tension or removal force is applied to the wire, the brake shoe is removed from contact with the reel to allow free 15 rotation thereof. When the tension is removed, the brake arm pivots to return the brake shoe to the initial contact position with the reel. The subsequent rotation of the reel then wedges the shoe downward in full contact with the flange thereby providing a significant 20 braking force to stop the rotation. Rotation of the reel in the opposite direction lifts the brake shoe out of its braking contact position into the initial contact position to allow rewinding of wire onto the reel. Because the brake is applied by the rotation of the reel rather than by the weight of a brake arm, the brake operates 25 when the reel is mounted for rotation about either a vertical or horizontal axis.

BRIEF DESCRIPTION OF THE DRAWINGS

30 The invention will be more fully comprehended from the following detailed description and accompanying drawing in which:

FIG. 1 is a perspective view of a brake in accordance with this invention mounted for utilization with a wire reel; and

35 FIG. 2 is a perspective view of the brake utilized in FIG. 1.

DETAILED DESCRIPTION

40 FIG. 1 shows a wire reel 2 having wire 4 wound thereon and rotatably mounted on a shaft 6 to a support arm 8. Support arm 8 is mounted to a base 10 which can comprise a frame or other appropriate mounting arrangement. Wire reel 2 includes two generally circular flanges 12 and 14 for preventing wire 4 from spilling from the edges of the reel 2. The inner or opposing surfaces or faces of flanges 12 and 14 are generally planar smooth surfaces. In accordance with this invention, a brake 20 is utilized for arresting the rotation of reel 2 and thereby controlling the winding or unwinding of wire 4 on reel 2. As shown more fully in FIG. 2, brake 20 comprises a base 22 having a brake arm 24 pivotally mounted thereto by pin or shaft 26. Arm 24 has a slot on cutout 28 along the top edge thereof in which a generally spool-shaped wire guide 30 is mounted. On the end of arm 24 is mounted a generally disc-shaped brake shoe 32 which can comprise a variety of well-known friction materials.

45 Brake 20 is mounted with pin 26 substantially perpendicular to shaft 6 of reel 2. In the illustrative embodiment, arm 24 is positioned between flanges 12 and 14 so that the face 32b of brake shoe 32 opposes the inside surface 14a of flange 14. For reasons to become apparent subsequently, brake 20 is mounted on the side of center line 34 on which the rotation of reel 2 for wire removal as indicated by arrow 36 has a component directed into the base 22 of brake 20. In the illustrative

embodiment of FIG. 1, brake 20 is mounted to the left of vertical center line 34 as viewed along shaft 6 in the direction of support 8 so that flange 14 has a velocity or rotation component at the point of contact with shoe 32 which is directed vertically downwardly into base 22.

Wire being removed from reel 2 is fed underneath guide 30 and can be taken in a plurality of directions as indicated by arrows 38 and 40. When a tension or removal force is applied to wire 4, the vertical component of this tension causes arm 24 to rotate about pin 26 and lift shoe 32 from contact with the inner face 14a of flange 14. Thus, reel 2 is free to rotate and unwind wire 4 in response to the tension thereon. When the tension on wire 4 is removed, arm 24 rotates under its own weight until the bottom portion of shoe 32 generally indicated by the number 32a establishes initial contact with the inner surface 14a of flange 14. At this point, face 32b of shoe 32 is not flush or parallel with the face of flange 14, i.e., the axis 46 of shoe 32 is not perpendicular to face 14a, and only a small or negligible braking force is applied by the relatively small contact area 32a. The vertical component of force generated by any subsequent rotation of reel 2 in the direction of arrow 36 forces arm 24 downward because of the frictional contact between face 14a and area 32a until face 32b of shoe 32 is wedged into a braking contact position substantially flush with face 14a of flange 14 and thereby applies a relatively large braking force to the reel. The transition from the negligible or relatively small braking force in the initial contact position to the large braking force in the braking contact position is smooth because the application of the braking force is controlled by the rotation of the reel rather than by the weight of brake arm 24. Brake 20 operates as a disc brake on the face 14a of flange 14 and accordingly is much more efficient than presently used brakes which apply the braking force to the flange periphery. When a tension or removal force is reapplied to wire 4, arm 24 again is pivoted upward to remove shoe 32 from the braking contact position and thereby again allow free rotation of the reel.

If reel 2 is rotated in the opposite or rewind direction, i.e., opposite to the rotation indicated by arrow 36, the vertical force component exerted on shoe 32 by the rotation of flange 14 is directed upwardly and thus shoe 32 never becomes wedged in the braking contact position previously discussed but remains in the initial contact position. Accordingly, brake 20 offers a negligible braking force to the rewinding of wire onto reel 2. This is a significant advantage over existing brakes which operate in both directions of rotation.

The actual amount of braking force applied to flange 14 can be adjusted by slightly shifting the mounting position of brake 20 with respect to the flange. This is accomplished by shifting the position of the mounting bolt or screw 42 in mounting slot 44 to move shoe 32 closer to or further away from flange 14. If brake 20 is shifted toward flange 14, shoe 32 will initially contact flange 14 along a smaller area of contact, i.e., the angle between axis 46 and the perpendicular to face 14a will be larger, and the subsequent wedging of shoe 32 against flange 14 will develop higher normal forces and hence higher braking forces. On the other hand, movement of brake 20 away from flange 14 reduces the braking force by reducing the normal forces developed by the wedging action.

Brake 20 operates even when reel 2 is mounted horizontally, i.e., mounted for rotation about a vertical shaft, as long as brake arm 24 is directed downward with shoe 32 above the flange with which it makes contact. The center of gravity of arm 24 is located so that even when brake 20 is mounted in the vertical position, i.e., base 22 is mounted against a vertical surface with arm 24 directed downward, arm 24 tends to rotate under its own weight toward base 22 until axis 46 of shoe 32 is substantially perpendicular to the face of flange 14. In other words, arm 24 tends to rotate toward base 22 until face 32b of shoe 32 is flush with face 14a of flange 14. However, as previously discussed, contact between area 32a and face 14a of flange 14 occurs before this amount of rotation is achieved and the braking action is subsequently applied by the continued rotation of reel 2. Operation with reel 2 oriented horizontally clearly cannot be accomplished by brakes which are activated solely by the weight of an arm which is pivoted about an axis parallel to the axis of the reel.

The foregoing discussion has been directed toward an application of the brake where a braking force is desired in only one direction of rotation. If bidirectional braking is desired, two of the described brakes could be utilized. One brake could be placed on each side of vertical center line 34 and braking in both directions of rotation could be provided. Alternatively, brake arm 24 could readily be modified to include two fingers or flanges on which are mounted brake shoes adapted for 20 contacting the reel flange on respective sides of vertical center line 34. A single wire guide could be utilized to rotate the brake arm in response to a tension in the wire. The brake shoes on the respective sides of center line 34 can provide braking in respective directions of rotation.

While the invention has been described with reference to a specific embodiment thereof, it is to be understood that various modifications might be made thereto without departing from the spirit and scope of the invention.

What is claimed is:

1. A brake for a wire reel mounted for rotation for winding and unwinding of wire thereon and having at least one flange for holding said wire thereon comprising, in combination:

a base;

a brake arm pivotably mounted on said base and having the center of gravity thereof located to cause said arm to rotate toward said base;

a brake shoe mounted on one end of said arm and adapted to apply a braking force to said flange, said shoe having a first edge portion adjacent said base;

means for mounting said base with respect to said flange so that only said first edge portion of said shoe initially contacts said flange and so that said flange has a component of rotational movement directed toward said base during said unwinding of said wire from said reel which applies a force to said first edge portion of said shoe to pivot said arm toward said base and wedge said shoe into increased contact with said flange to apply said braking force thereto; and

means including a wire guide on said arm responsive to a force unwinding said wire from said reel for pivoting said arm away from said base and removing said shoe from contact with said flange to allow free rotation of said reel.
